FLUSHING FOR WATER CLOSETS

Filed May 27, 1929

FIG. 1

FIG. 2

FIG. 3

FIG. 4

Paul E. Georgiou
INVENTOR

UNITED STATES PATENT OFFICE

PAUL E. GEORGIU, OF BINGHAM, UTAH

FLUSHING FOR WATER-CLOSETS

Application filed May 27, 1929. Serial No. 366,336.

The invention relates to water closets of that type in which the water for flushing the bowl is forced by the air pressure being obtained by utilizing the pressure in the water mains; and has for its object, first, to provide a valve novel and efficient to control filling and flushing, which operates without spring and has no packing or parts working under significant friction, with the resultant advantage of saving in equipment and wear; and, second, to obtain, without wastage, just sufficient water to reestablish the water seal in the bowl, after the bowl has been flushed.

One form of the invention is illustrated in the accompanying drawing, in which Figure 1 is a vertical section through a portion of the bowl and the reservoir showing the compartment and the valve applied thereto; Figure 2 is a section longitudinally and vertically through the operating valve, with dotted lines to indicate the water channel; Figure 3, is a section of the valve cap and the valve stem; Figure 4, is a section on line 4—4 of Figure 2 after the removal of the valve cap and closure valve.

A water closet bowl 1 and a pneumatic flushing reservoir 2 are preferably formed integral. This reservoir connects, at a suitable point (not shown), with a supply pipe 30 leading from the water main. Adjacent to the said reservoir is a water compartment 3 provided with discharging port 4 and an overflow port 5 on the front side thereof and which has a cover 6 thereover. In this compartment the control valve 7 is placed. The outlet end 8 of this valve is in open connection with the usual flushing passages. Through an elbow 9 communication is had of the inlet end 10 of the valve 7 with the pipe 11 by means of the joint 12 secured to the compartment floor. The valve 7 and pipe 11 are of considerably larger diameter than the water supply pipe.

The control valve 7, shown in longitudinal and vertical in Fig. 2, has an open bottom cylindrical chamber 13 formed at the annularly open top side of the valve casing 14 threaded at 15 for the reception of a closure cap 16 formed with and around the outer edge

depending annular and internally threaded flange 17.

The closure valve is made of a valve stem 18 having a frusto-conical member 19 formed medially therearound and with the lower end 20 enlarged and semi-conical in shape, with the bottom end thereof hollowed at 21. A preferably hollow rubber valve 22 fits tightly around the stem 18 and against the flange 19 with the enlarged end 20 to hold it in place thereon. The stem 18 is adapted to keep the valve in alignment over the valve seat 23 by freely fitting up into a guide 24 provided by a centrally and from the bottom side bored boss 16^a which is concentrically formed on the top side of the cap 16. The flange 19 is of slightly smaller diameter than the chamber 13, so that when the closure valve, forced upwardly by the incoming water, starts entering said chamber, as shown in Fig. 2, traps the water therein, which slowly then escapes therefrom to avoid violent contact at the top of the valve.

The inlet end 10 of the valve 7 is formed so that the incoming water will completely surround the valve seat 23 from all sides and to accomplish this an annular groove 25, with the dotted line 26 showing its lower side, is formed therearound, so that when the closure valve is raised off its seat, the upward pressure of the incoming water is equal at all sides of the said valve, with the result that the friction of the stem 18 and guide 24 is little as possible.

Within and on the under side of the casing 14, in the outlet end of said casing a boss 27 is formed which is centrally bored at 28 to receive the control valve stem 29. The bore 28 is of larger diameter than the stem 29, so that the stem may work freely therein and water will also pass downwardly around the stem, when it is flowing out through the outlet end of the valve.

Ports 30 may be bored at the under side of the casing around the boss 27, so that sufficient water may pass through the said ports and around the stem 29 to completely fill the compartment 3 when the valve has been operated to flush the bowl.

The stem 29 pivoted on the longer arm of a

lever 31 actuates by manipulation of a plunger 32 pivoted on the opposite end of the lever 31 and mounted outside the compartment 3 in a position for convenient access by the user.

5 The operation will be readily understood. With the valve normally closed, when the main supply is introduced water will flow into the reservoir 2 until the air therein is compressed to a point to balance the pressure in the water mains; the closet will then be ready for flushing. Manipulation then of the plunger 32 actuates the stem 29 which engages in the hollowed end 21 and unseats the 10 valve 22 to be raised fully open by the pressure of the incoming water, while the trapped water in the chamber 13 escapes slowly therefrom. With the valve then fully open the flushing water will flow with force through the valve into the flushing passages until the 15 air in the reservoir 2 has reached atmospheric pressure at which time the said water slowly and without force passes the valve; then the forces of gravity drop the valve 22 into its seat; the downward pressure of the water on flange 19 will then hold the valve closed and the water flowing from the supply pipe into the reservoir 2 starts filling it again. 20 While the flushing water passes the valve some of it will pass downwardly through the 25 ports 30 and around the stem 29 to fill the compartment 3; should the compartment become overfull, the overflow 6 will allow the 30 excess water to flow down into the bowl and aid flushing; the water in the compartment 3 will flow out through the port 4 to again establish the water seal in the bowl after the 35 bowl has been flushed.

It may be remarked that, the details of 40 construction herein shown and described may be varied, if only the essentials of the invention, as pointed out in the appended claims, are maintained.

I claim:

45 1. A water closet comprising a pneumatic compression reservoir for storing water to flush the bowl, a pipe connecting the reservoir with the rim of the bowl for conducting the flushing water thereinto, a valve in said 50 pipe between the reservoir and the rim of the bowl, a water compartment in which said valve is located provided with overflow and drainage openings and having a capacity sufficient to supply the water seal for the bowl, 55 means adapted to be manipulated by the user for opening said valve and means associated with the valve for filling said compartment when the valve is opened for flushing the bowl.

60 2. A water closet as in claim 1, wherein the valve is mounted for free floating movement adjacent a chamber adapted to form a water check for the valve so that it will open slowly and avoid wear by violent contact.

65 3. A water closet as in claim 1, wherein

guiding members support the valve and the inlet end of the valve casing is formed so that, when the valve is raised, the pressure of the incoming water is equalized on all sides of the said valve thereby reducing the friction and wear of the guiding members.

4. A water closet as in claim 1 wherein the means for filling said compartment comprises openings in the casing enclosing said valve through which a small amount of water escapes into the compartment when the valve is opened, the main stream for flushing the bowl passing through the pipe into the flushing rim.
